UNITED STATES PATENT OFFICE.

JOHN A. MARKOE, OF ST. PAUL, MINNESOTA.

STAMPER-FEED.

1,066,027.

Specification of Letters Patent.

Patented July 1, 1913.

Application filed June 28, 1911. Serial No. 635,868.

To all whom it may concern:

Be it known that I, JOHN A. MARKOE, a citizen of the United States, residing at St. Paul, in the county of Ramsey and State of Minnesota, have invented new and useful Improvements in Stamper-Feeds, of which the following is a specification.

This invention relates to an improved packet feeding mechanism adaptable particularly to stamp applying machines, the invention referring particularly to an improvement upon the feeder disclosed in co-pending application for a stamp affixer machine, filed February 13, 1911, Serial Number 608,424.

The principal objects of the invention are: to insure a positive and uninterrupted feed of the packets into the machine from the table; to admit of the placing of the packets in superimposed relation upon the table, or resting one upon the other; and to feed the packets singly into the machine from the bottom of the pile.

With these objects in view the invention in a general way comprises a table upon which the packets are arranged, guides disposed upon the opposite sides of the pile of packets to hold the same one above the other and in alinement with the feeder, and a forwardly revolving initial feeding roller extending up through the table and yieldingly bearing against the lowermost packet to slide the same forwardly into the main portion of the feeder.

Other and further objects of this invention will be hereinafter disclosed in the improved construction and combination of the parts of the feeder specifically brought out in the description, the accompanying drawings, and more particularly in the appended claims.

In the accompanying drawings in which corresponding parts are indicated by like reference numerals throughout the views, Figure 1 is a longitudinal section, taken through the stamper feed; Fig. 2 is a top plan view of the same; and Fig. 3 is a detail enlarged view of one of the bearings for the shaft of the separating roller.

Referring to the drawings, 10 designates a frame of a stamp applying machine which is of any approved and adaptable form, and upon which is disposed the improved stamper feed forming the subject-matter of this application. The frame is provided

with spaced side members supporting across one end a table 11, adapted to receive the packets which are fed into the stamper machine. Disposed in the frame 10 immediately below the inner edge of the table 11 is a main feeding roll 12 fixed upon a transverse shaft 13, suitably mounted in the frame 10. The main feeding roll 12 is provided with a number of spaced peripheral grooves for the reception of rubber bands 14, exposed through the whole periphery of the main roll. The roll 12 is so positioned in the frame 10 that it projects up in flush relation with the upper face of the table 11, and is adapted to receive packets from the table.

Within the frame 10, above the main feeding roll 12 and spaced slightly forward of the same, is a transverse shaft 15 having its ends journaled in eccentrics 16 rotatably mounted in hollow bosses 17 formed upon the side members of the frame 10. Thumb screws 18 project through the hollow bosses 17 and bind against the eccentrics 16 to hold the same fixedly in position when adjusted. This peculiar mounting of the shaft 15 admits of the adjustment of the same toward and from the main feeding roll 12. Intermediate of the ends of shaft 15 a relatively narrow spacing roll 19 is disposed, the same being preferably provided with a yielding outer surface or periphery, formed of rubber or the like, for contact with the under surfaces of packets passing over the main feeding roll 12.

A guard plate 20 engages across the frame 10 immediately above the main feeding roll 12, the same comprising a vertical portion receiving thereagainst the forward edges of the packets, and having a forwardly curved lower edge terminating adjacent to the periphery of the feeding roll 12 to admit of the passage of a single packet over the feed roll 12. The main feeding roll 12 rotates in a forward direction to carry the packets from the table 11 into the stamper machine, while the spacing roll 19 operates in a reverse direction to retain or move backwardly an upper packet or packets should more than one of the same pass onto the main feeding roll 12 from the table 11.

Within the frame 10, and spaced forwardly from the main feeding roll 12 and the spacing roll 19, are a pair of moistening rollers 21 and 22, which are adapted to re-

ceive the packets as they pass from the main feeding roll. The specific construction and operation of these moistening rollers 21 and 22 has been clearly set forth in the above referred to application, and as they form no part of the present invention, further description of the same is deemed unnecessary. The roller 22 is connected for operation to the main feeding roll 12 by a chain 23 held taut and out of the path of the packets by an idler 24. A platform 25 bridges the space between the main feeding roll 12 and the spacing roll 19 and the moistening rollers 21 and 22, the platform 25 directing the packets between the moistening rollers 21 and 22.

The frame 10 carries an initial feeding roll 26 having a preferably rubber periphery and projecting up through a transverse slot 27 formed in the table 11, at a point spaced rearwardly from the main feeding roll 12. The initial feeding roll 26 projects slightly above the upper surface of the table 11, and engages the lower face of the lowermost packet to impart a forward sliding movement to the same. The initial feeding roll 26 is considerably reduced in size relative to the main feeding roll 12, and receives movement therefrom in a forward direction by a chain 28 held taut beneath the table 11 by an idler 29. As may be seen from Fig. 1 of the drawing, the initial feeding roll 26 is so geared to the main feeding roll 12 by the chain 28 that the initial feeding roll 26 is revolved continuously at a relatively high rate of speed as compared to the angular velocity of the main feeding roll 12. The initial feeding roll 26 is mounted upon a shaft 30, serving as a tie rod in the frame 10. At one side of the table 11 is a guide 31 preferably fixed upon the frame to hold the packets in superimposed relation upon the table, while an adjustable guide 32 is slidably disposed upon the table 11 and preferably has connection with the shaft or tie rod 30 to hold the guide 32 firmly when adjusted. From this structure it will be understood that the initial feeding roll 26 has a relatively high angular velocity as compared with the angular velocity of the main feeding roll 12, and that therefore the lowermost packets which bear upon the initial feeding roll 26 are fed quickly and uninterruptedly to the main feeding roll, for a purpose which will appear from the hereinafter described operation of the device.

From the foregoing description it will readily be seen that the operation of the improved device is as follows: A number of packets is disposed upon the table 11 against the guide 31 and in superimposed relation. The packets are pushed forwardly against the guard plate 20 and the adjustable guide 32 is moved into position against the oppo-

site edges of the packets. The main feeding roll 12 is now revolved, which operation effects the turning of the initial feeding roll 26. As the packets rest upon the initial feeding roll 26 the lowermost packet is moved forwardly over the table 11 into engagement between the main feeding roll 12 and the spacing roll 19. Should, by accident, two packets pass together onto the main feeding roll, the separating roll 19, 70 revolving in a backward or reverse direction, engages the upper face of the upper packet and forces the same backwardly toward the initial feeding roll 26. This operation admits of the passage of but one packet at a time to the moistening rollers 21 and 22. When the packets are piled up upon the bed plate they are supported at their middle portions upon the initial feeding roll 26. The initial feeding roll 26 therefore, supports practically the entire weight of the superposed packets, and there is thus a greater frictional contact between the initial feeding roll 26 and the packets than between the packets and the bed plate 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790

The packets may be piled indefinitely upon the table 11 between the guides 31 and 32 as the improved device feeds the packets 130

from the bottom of the pile and does not interfere with the placing of additional packets upon the table.

Having fully described my invention what I claim as new is:—

1. In combination with a main feed roll, a reversely rotating separating roll arranged above the feed roll, a guard plate disposed immediately behind the separating roll, and 10 a bed plate projecting rearwardly from the top of the main feed roll adapted to support a pile of superposed packets, an initial feed roll extending up through the middle portion of the bed plate and adapted to support 15 the middle portion of the pile of packets whereby said initial feed roll is adapted to move the lowermost packet forwardly a short distance until the forward end of said packet engages the main feed roll, the friction between said packet and the bed plate being greater than the friction between the initial feed roll and the rear end of the packet whereby the packet is drawn forwardly by the main feed roll at a reduced 20 rate of speed, the rear end of the lowermost packet resting against the initial feed roll whereby to prevent contact of said initial feed roll with the next adjacent packet.
2. An automatic feeding device comprising 25 a forwardly rotating main feed roll, a reversely rotating separating roll bearing down upon the feed roll, a bed plate extend-

ing backwardly from the top of the main feed roll and adapted to support a pile of superposed packets, a guard plate rising 35 from the forward end of the bed plate adjacent said separating roll, and an initial feed roll extending up through the middle of the bed plate and adapted to bear against the middle portion of the pile of packets whereby to prevent the pile of packets bearing its full weight upon the bed plate and having an angular velocity greater than the angular velocity of the main feed roll whereby to quickly and uninterruptedly move the lowermost 40 packet to the main feed roll, a distance sufficient to dispose the middle portion of said packet forwardly of the initial feed roll, the frictional contact between the bed plate and the lowest packet when moved forwardly being greater than the frictional contact between the initial feed roll and the rear end of the packet whereby the movement of said packet is reduced to the speed of the main roll and the initial feed roll is 45 held from contact with the next lowermost packet.

In testimony whereof I have hereunto set my hand in presence of two subscribing witnesses.

JOHN A. MARKOE.
